UNITED STATES PATENT OFFICE

1,999,606

COLLAPSIBLE SPOOL

Samuel D. Grumney, Hampton, and Ralph H. Carter, Johnson City, Tenn., assignors to North American Rayon Corporation, a corporation of Delaware

Application July 14, 1932, Serial No. 622,524

7 Claims. (Cl. 242—113)

Our present invention relates to improvements in take-up spools for twisting machines and the like, and, more particularly, to an improved take-up spool having collapsible sections which will 5 permit of the even drying of the yarn wound thereon from the twister, the collapsing being so arranged as to compensate for the shrinkage of the damp twister thread wound thereon. By the use of our new type of spool undue tension 10 in the drying thread is avoided.

Our present invention also contemplates, by the use of our improved collapsible spool, an improved method for the twisting and drying of threads and/or filaments of artificial thread and 15 analogous products.

It is therefore an object of our present invention to provide a spool built up of a plurality of sections so arranged as to be moved inwardly toward the axis of said spool during the drying of 20 the thread wound thereon during twisting. By the use of such a spool the spun thread, and/or filaments, after the usual wet treatments, may be removed from the dryer while in a comparatively wet state as compared with the usual method 25 of drying wherein very little moisture is retained by the thread after the completion of the drying operation. After removal from the dryer the spools of comparatively wet threads are then placed in a twisting mechanism, and the thread 30 after twisting is collected on our new collapsible spool. Because of the "fanning" effect of the rotating spindle and the "ballooning" of the thread during twisting, the moisture content thereof is considerably reduced and it is consequently comparatively dry when wound on our new spool. The final shrinkage of the thread is compensated 35 for by the collapsibility of the spool.

Still another object of our present invention is to provide a collapsible take-up spool wherein 40 movable sections thereof are held normally against the driving flanges of the spool but which are adapted to move inwardly as the thread wound thereon dries. By such construction there is no tension placed on the thread during drying.

A further object of our present invention is to provide an improved collapsible spool primarily adapted for use on twisting machines. Such a spool will facilitate the rewetting and redrying 45 of the thread in practicing the process outlined in the copending application of Ralph H. Carter, Serial Number 623,007, filed July 16, 1932, now Patent No. 1,955,323 of April 17, 1934.

These and other objects of our present invention will become more apparent from a study of

the following description, and by reference to the attached drawing, wherein:

Figure 1 is a sectional view of our new collapsible spool taken along the lines 1—1 of Figure 2; and

Figure 2 is a sectional view taken along the lines 2—2 of Figure 1.

Referring now more particularly to the drawing in which like numerals indicate like parts, our new collapsible spool comprises a central 10 shaft or rod 10 to which are secured in any suitable manner, such as by nuts 11, the perforated end plates or disks 12. As will be seen from an inspection of Figure 1, the end plates or disks are provided with flanges 13 which not only limit 15 the outward movement of the movable sections of the spool, but provide driving surfaces against which the take-up rollers 14 contact. This method of driving the take-up spool avoids contact between the take-up roller and the thread on the 20 spool, such contact being rather injurious to the thread, and is an improvement over the driving mechanisms now commonly used in the art.

The thread carrying portion of the spool comprises a plurality of segments 15 which are each 25 provided with spaced shells or tubular members 16, having telescoping engagement with pins 17 projecting outwardly from the shaft 10. The segments are held normally against the inner surface of flange 13 of the end plates by means of springs 30 or other resilient means 18 resting against the bottom of the tubular members or shells 16 and against the ends of the pins 17. As will be noted from an inspection of Figure 2, the segments, in 35 their outward position, are not in contact with each other, spaces 19 being provided to permit their movement toward the shaft 10. The construction of the end disks is such as to protect the movable section of the spool against damage, should the spool be accidentally dropped.

The spool is held in driving position by means of pins 20 which are adapted to be journaled in the usual supporting bearings (not shown) in the machine.

In operation the spools of thread are removed 45 from the drier in a damp condition and placed on the conventional twisting spindles. The thread passing from each twister is then collected on our new collapsible spool. Because of the rotation of the spindles and the ballooning of the thread 50 during twisting, the moisture content of the thread is still further reduced. If desired, means may be provided above the twisting spool to subject the thread to hot air to aid in the drying of the thread. The thread, as it is wound on the 55

collapsible spool, is still slightly damp, and as it dries on the spool the shrinkage is taken care of by the collapsing of the spool, thereby preventing the setting up of undue tension in the thread.

- 5 From the above description it will be appreciated that we have provided a new and improved method of and device for the drying of threads by which undue tension in the thread is avoided by providing a collapsible surface upon which 10 the thread, while still in a damp condition, is wound.

While we have described our invention with reference to the specific embodiment shown, it will be appreciated to those skilled in the art that 15 many minor changes may be made without departing from the spirit of our invention or the scope of the appended claims.

What we desire to claim as new is:

1. A collapsible spool comprising, in combination, a central shaft, perforated disks secured to 20 the ends thereof and provided with depending circumferential flanges, spaced pins secured to said central shaft and positioned between said disks, perforated segmental shaped sections carrying 25 tubular members telescopingly engaging with said pins, springs positioned in said tubular members normally pressing said segmental portions outwardly, the outward movement thereof being limited by said flanges.
- 30 2. A collapsible spool comprising, in combination, a central shaft, disks secured to the ends thereof and provided with depending circumferential flanges, spaced pins secured to said central shaft and positioned between said disks, segmental shaped sections carrying tubular members 35 telescopingly engaging with said pins, springs positioned in said tubular members normally pressing said segmental portions outwardly, the outward movement thereof being limited by said flanges.
- 40 3. A collapsible spool comprising, in combination, a central shaft, end disks secured thereto, a yarn supporting body made up of a plurality of spaced segmental plates, and movably connected 45 to said shaft, means normally to press said plates outwardly, said means positioned between said

disks, and means on said disks to limit the outward movement of said plates.

4. A collapsible spool comprising, in combination, a central shaft, perforated disks secured to the ends thereof and provided with depending circumferential flanges, spaced pins secured to said central shaft and positioned between said disks, perforated segmental shaped sections carrying 5 tubular members telescopingly engaging with said pins, means positioned in said tubular members normally pressing said segmental portions outwardly, the outward movement thereof being limited by said flanges.

5. A collapsible spool comprising, in combination, a central shaft, perforated disks secured to 15 the ends thereof, spaced pins secured to said central shaft and positioned between said disks, perforated segmental shaped sections carrying tubular members telescopingly engaging with said pins, springs positioned in said tubular members 20 normally pressing said segmental portions outwardly, and means to limit the outward movement of said sections.

6. A collapsible spool comprising, in combination, a central shaft, perforated disks secured to 25 the ends thereof, spaced pins secured to said central shaft and positioned between said disks, perforated segmental shaped sections carrying tubular members telescopingly engaging with said pins, springs positioned in said tubular members 30 normally pressing said segmental portions outwardly.

7. A collapsible spool comprising, in combination, a central shaft, perforated disks secured to the ends thereof and provided with depending circumferential flanges, spaced pins secured to said central shaft and positioned between said disks, spaced perforated segmental shaped sections carrying tubular members telescopingly engaging with said pins, springs positioned in said 35 tubular members normally pressing said segmental sections outwardly, the outward movement thereof being limited by said flanges.

SAMUEL D. GRUMNEY.
RALPH H. CARTER.
